UNITED STATES PATENT OFFICE

PAUL MELYAN, OF CHICAGO, ILLINOIS

TOP-SPINNING HANDLE

Application filed May 23, 1932. Serial No. 613,045.

This invention relates to certain novel improvements in top-spinning handles, and has for its principal object the provision of an improved construction of this character which will be highly efficient in use and economical in manufacture.

It is an object of this invention to provide a novel, simple, and inexpensive top-spinning handle and to construct the same so that it can readily be accommodated to tops having spindles of various sizes.

Another object of the invention is to provide on the top-spinning handle a novel wing member or plate onto which the top may be lifted when spinning so that the handle and attached wing member may be held in the hand while the top is spinning on said plate or wing member, thereby to afford a novel and amusing effect.

Other objects will appear hereinafter.

The invention consists in the novel combination and arrangement of parts to be herein-after described and claimed.

The invention will be best understood by reference to the accompanying drawing, showing the preferred form of construction and in which:

Fig. 1 is a respective view of a preferred form of the invention;

Fig. 2 is a sectional view on line 2—2 in Fig. 1;

Fig. 3 is a bottom plan view on line 3—3 in Fig. 2; and

Fig. 4 is a sectional view on line 4—4 in Fig. 3.

In the drawing 10 indicates generally my novel top-spinning handle which comprises two sections 11 and 12 that are hingedly connected together at one end of the handle by means of a resilient strap 13 or other suitable hinge connection. Disposed between the two handle sections 11 and 12 and urging the same apart is a flat spring member 14 which has one end attached as at 15 to the handle section 12.

Movement of the handle sections 11 and 12 relative to each other is limited by means generally indicated at 16 and including a strap 17, which has one end attached to the handle section 12 at 18; the other end portion of the strap 17 being provided with a slot

19 through which projects a headed pin 20 attached to the handle section 11.

The handle sections 11 and 12 are normally urged apart at their free ends 21 by the spring member 14 so that the diameter of the spindle-receiving ring or opening 22 which the handle sections cooperate to provide may be varied by pressing the handle sections toward each other against the action of the spring member 14 whereby to accommodate the size of the ring 22 to varying diameters of spindles such as 23 of different tops such as 24.

The spinning cord 25 is preferably fed through a slot 26 in one of the handle sections, and wound about the top spindle 23 in a conventional manner, but the cord 25 may be left entirely free of the handle if desired.

The top is released from the handle 10 in a conventional manner, by exerting a quick pull on the free end of cord 25. To one of the handle sections I attach, as at 27, a flanged plate or wing 28 which projects laterally from the handle 10 and has a flared mouth 29.

After the top has been set spinning on a surface the handle 10 may be lowered down to the surface, the edge 29 of the plate 28 pressed against the surface under the rotating spindle of the top, and the spinning top guided over the flared mouth or edge 29 of the plate 28 up onto the same whereby the handle 10 and the plate 28 may be held in the hand while the top is spinning on the wing or plate 28, thereby creating a novel and amusing effect.

While I have illustrated and described the preferred form of construction for carrying my invention into effect, this is capable of variation and modification without departing from the spirit of the invention I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A top spinning handle comprising a pair of sections hingedly connected together, each of said sections having a recess provided

therein on its inner side, and said recesses cooperating with each other to provide in the handle a top spindle-receiving opening adapted selectively to receive one at a time top spindles of varying diameters.

2. A top spinning handle comprising a pair of sections hingedly connected together at one end of the handle each of said sections having a recess provided therein on its inner side, said recesses cooperating with each other to provide in the other end portion of the handle a top spindle-receiving opening adapted selectively to receive one at a time top spindles of varying diameters, and a spring member carried by said handle between said handle sections and normally urging said sections apart.

3. A top spinning handle comprising a pair of sections hingedly connected together at one end of the handle each of said sections having a recess provided therein on its inner side, said recesses cooperating with each other to provide in the other end portion of the handle a top spindle-receiving opening adapted selectively to receive one at a time top spindles of varying diameters, a spring member carried by said handle between said handle sections and normally urging said sections apart, and means associated with said sections limiting the extent of movement of the same relative to each other by said spring member.

In testimony whereof I affix my signature.
PAUL MELYAN.
